CALCULATING MACHINE

Chester J. Abend, Camillus, and James H. Frakes, Jr.,
Manlius, N.Y., assignors to SCM Corporation, New
York, N.Y.

Filed Apr. 29, 1971, Ser. No. 141,813

Term of patent 14 years

Int. Cl. D18—02

U.S. Cl. D64—11

Fig. 1

Fig. 2

Fig. 3

Fig. 4

FIG. 1 is a front perspective view of a calculating machine with the cover open showing our new design;

FIG. 2 is another front perspective view of the calculating machine shown in FIG. 1 as it appears with the cover in closed position;

FIG. 3 is a top plan view thereof;

FIG. 4 is a front elevational view thereof;

FIG. 5 is a rear elevational view thereof;

FIG. 6 is a left hand elevational view thereof;

FIG. 7 is a right hand elevational view thereof;

We claim:

The ornamental design for a calculating machine, substantially as shown.
